UNITED STATES PATENT OFFICE.

JOSEPH D. LACROIX, OF BALTIMORE, MARYLAND, ASSIGNOR TO THE WILSON DISTILLING COMPANY, OF JERSEY CITY, NEW JERSEY, A CORPORATION OF NEW JERSEY.

SPINNING-MACHINE FOR BOTTLES.

1,273,878.

Specification of Letters Patent.

Patented July 30, 1918.

Application filed October 24, 1912. Serial No. 727,492.

To all whom it may concern:

Be it known that I, JOSEPH D. LACROIX, a citizen of the United States, residing at Baltimore, State of Maryland, have invented certain new and useful Improvements in Spinning-Machines for Bottles, fully described and represented in the following specification and the accompanying drawings, forming a part of the same.

10 This invention relates to capping machines, and in particular to machines adapted to seal caps upon receptacles by spinning.

In the accompanying drawings—

Figure 1 is a sectional elevation of a capping machine embodying the improvements of the present invention;

Fig. 2 is a sectional elevation of the spinning mechanism of the machine;

Fig. 3 is a horizontal section on the line 6 of Fig. 2;

Fig. 4 is a horizontal section on the line 7 of Fig. 2; and

Figs. 5 and 6 are sectional elevations on the line 8 of Fig. 3.

25 The particular mechanism herein shown as disclosing the invention consists of a machine for the sealing of separately constructed necks to bottles where the combined neck and bottle form a non-refillable receptacle.

30 The main frame of the machine, as shown in Fig. 1, comprises the base 10 and a vertical tubular standard 11.

The principal part of the mechanism is mounted upon a turret frame which rests 35 upon the base 10 and is adapted to rotate about the vertical standard 11. The upper part 12 of the turret forms a framework carrying the spinning devices indicated at 13, 13 and the lower part 14 forms a framework carrying respective holders indicated at 15, 15. The upper and lower sections of the turret are joined together by tie rods 16, 16.

The upper section 12 is keyed to a sleeve 17 which is located within the tubular standard 11 and is concentric therewith. The sleeve 17 at its lower end is keyed to a gear 18. The lower section 14 bears upon the outer surface of the tubular standard at 19 and is keyed to its base a gear 20 of the same size as the gear 18.

5 The weight of the turret is carried by a step bearing 21 formed by a shoulder on the vertical standard 11, and by a circular flange 22 depending from the lower section 14 and

bearing upon centering rollers 23, 23, supported in brackets attached to the main frame.

The turret is rotated by gears 18^a and 20^a which are attached to shaft 24 and mesh with gears 18 and 20 respectively. The shaft 24 is driven by a train of gears leading from the power shaft 25. This train includes the worm 26, worm wheel 27, and gears 28, 29, 30 and 31.

60 The worm wheel 27 is keyed to a solid shaft 32 which passes upward through the vertical standard to the upper part of the machine where it carries a spur gear 33 which meshes with the spur gears 34, 34 attached to the individual spinning devices.

65 By means of the gearing thus described and shown, the application of power to the shaft 25 will cause the turret to rotate slowly in one direction while the gear 33 will rotate at a greater angular velocity in the opposite direction. The rotation of the turret permits the continuous placing of bottles in the holders at one point, determines the subsequent automatic elevation of the holders at 70 another point so that the spinning devices may seal the neck to the bottle, and permits the ready removal of the bottles after they have been sealed.

75 The operation of the holders, the operation of the spinning devices, and the co-operation of the holders and the spinning devices are all controlled automatically by the movement of the turret through mechanism now to be described.

80 Referring to Fig. 1, each of the holders 15, equipped with a centering device 35, is carried upon a square piston rod 36 attached to a piston 37 in the cylinder 38. A pipe 39 communicates with the lower end of the cylinder 38 through an interposed valve 40. When compressed air or other fluid is admitted to pipe 39, it passes into the bottom of the cylinder, slowly raising the piston and holder 15. When the air is allowed to escape, the piston and holder 15 descend. The supply of air to cylinder 38 and its escape therefrom will, of course, be suitably regulated, so that they will occur automatically and be properly timed with relation to the 90 desired movement of the holder 15.

95 The turret is equipped with a commutating device which controls the admission and escape of air from the cylinder 38. Each of the pipes 39 communicating with the re- 100

110

spective holder cylinders 38 is hung upon the turret frame 12, 12 and terminates in a circular valve seat 43, the lower face of which has a port opening 44 for each individual pipe. The valve seat 43 rotates with the turret. Keyed to the standard 11, but 5 slide vertically thereon, are two rings 45 and 46 held in contact with each other, and the intermediate one with the valve seat 43 by means of springs 47, 47. The lower ring 46 has a pipe 48 attached thereto through which compressed air or other fluid is continuously supplied to a semi-circular channel not shown formed in the upper face of 10 the ring. The intermediate ring 45 has a similar channel 50 which is in communication with the semi-circular channel (not shown) in the ring 46. The ring 45 is also equipped with a second annular channel having exhaust outlets 52. It will be apparent 15 that one group of pipes 39 are in communication with the compressed air supply, while another group is in communication with the exhaust channel.

20 As the turret rotates, therefore, the bottle holders passing through a certain arc will be automatically elevated and will then return to their original loading and unloading position after having completed that 25 part of the rotation.

25 The springs 47 which effect the packing of the valves may cause more or less vertical movement of the pipe 48 and this is taken care of as follows: A supply pipe 53 is brought into the base of the machine and tapped into a channel 54 formed in the vertical standard 11. This channel terminates at the point 55 on the standard at which a hollow ring 56 encircles the standard with a 30 close sliding fit and receives one end of the pipe 48. This arrangement permits movement of the valve rings, pipe 48 and ring 56 without interrupting the air supply from supply pipe 53.

40 The spinning mechanism is adapted to seal hermetically together the neck and bottle by spinning a sleeve upon them. The method is disclosed in Figs. 5 and 6, in which the bottle is shown at 60 and the neck 50 at 61. The neck has a groove 61^a while the bottle has two similar grooves 60^a and 60^b. The sleeve or ferrule 62 as shown in Fig. 5 is provided with a flange 63 by which it may be set in position upon the neck and may 55 also serve to hold the neck in alignment with the bottle. The sleeve is spun into the grooves 61^a, 60^a and 60^b, firmly binding the neck and bottle together, as shown in Fig. 6; and during the spinning the sleeve 62 is 60 drawn or ironed out, as indicated in the two figures. The ironing out of the sleeve is due to an increasing pressure exerted by the spinning rolls as they travel down the sleeve. This is a desirable feature of the invention 65 as the pressure of spinning rolls tends at all

times to hold the neck firmly upon the bottle during the spinning process, and it also leaves that part of the sleeve joining the neck and the bottle under permanent tension so that the seal will not only be hermetic but 70 it will remain so.

The spinning mechanism comprises three coöperating devices: plungers operating together to center the neck, to hold it in position upon the bottle, and to clamp the sleeve 75 in position for spinning; mechanism to move the spinning rolls along the sleeve; and mechanism to vary the pressure of the spinning rolls upon the sleeve.

80 The centering and holding plungers are shown in Figs. 1, 2, 5 and 6. Centrally located in each spinning mechanism is a rod 64 best shown in Fig. 2. The upper end of this rod is anchored to a lug 65 carried by the upper framework 12 of the turret as shown 85 in Fig. 1. The intermediate part of rod 64 is hollowed out to receive a spring 66 and a plunger 67, the lower end of which terminates in a centering head 68. The lower part 90 of rod 64 is enlarged to form a cylinder within which a second and stronger spring 69 is located and also a second plunger 70, the plunger 67 passing freely through the spring 69 and the second plunger 70. At the lowest point on the rod 64, at the bottom 95 of the cylindrical enlargement, is a tubular jaw 71.

These devices operate as follows: When the bottle and neck are placed in position as shown in Fig. 2 and the holder is elevated 100 by the mechanism previously described, the neck 61 of the bottle first comes into contact with the centering plunger head 68, which acts to center the neck and bottle as the holder continues its upward movement, the 105 movement at the same time driving back the plunger head 68 and compressing the spring 66. Just before the holder reaches its upward limit of motion, the head 68 comes into contact with the lower end of the second plunger 70, whereupon additional pressure is put upon the neck 61 by the compression of the spring 69. This position of the parts is shown in Fig. 5. At the last instant of the upward movement of the holder, as also shown in the same figure, the tubular jaw 110 115 115 120 125 130 71 comes into contact with the flange 63 of the sleeve or ferrule 62 and clamps that part of the sleeve firmly to the cap.

The spinning rolls are shown at 72, 72, in Figs. 4, 5 and 6, and are carried by arms 73, 73 pivoted with their respective shafts at 74, 74, at equal distances from one another upon a spinner head 75. The head 75 is carried at the lower end of a rotary sleeve 76 which surrounds the plunger mechanism described above and is concentric with the fixed rod 64. As shown in Fig. 2, the upper end of the sleeve 76 carries a feather 77, and is slideable through a splined sleeve 78 130

to which the gear 34 previously described is keyed. The sleeve 78 rotates within a bearing formed in the upper turret section and is held in position by a nut 79.

5 By the construction thus described, the splined sleeve 78 communicates a continuous rotary motion to the sleeve 76 and the spinner head 75, at the same time permitting a longitudinal sliding movement of the sleeve 10 76 and the head 75 to take place. This longitudinal movement is effected by means of a sleeve 80 which surrounds the sleeve 76 but does not rotate therewith. The sleeve 80 is inset between a shoulder 81 and a bushing 15 82 carried by the sleeve 76. To the sleeve 80 is attached a rack 83 which meshes with a segment 84 fulcrumed to the turret frame at 85 and provided with an arm to which is pivoted at 86 an actuating link 87. Referring now to Fig. 1, the lower end of the link 87 is attached to a slide 88 mounted upon one of the turret tie rods 16. Projecting from the slide 88 is a stud carrying a cam roller 89 which moves in a circular cam 20 groove 90 cut in a stationary cylinder 104 attached to the tubular standard 11.

The pressure of the spinning rolls upon the sleeve is varied by the following mechanism. In Fig. 3, the shafts 74 carrying the spinning rolls 72 are shown equipped with arms 91 to which are fastened resilient members 92, 92 terminating at their inner ends in friction balls 93, 93. These balls normally contact with a hollow cone 94 which is slid-
 30 able longitudinally upon the spinner sleeve 76 and the spinner head 75. As shown in Fig. 1, the cone 94 has a groove 95 through which it is engaged by yoke 96. The yoke is attached to a rack 97 which engages a
 35 segment 98 fulcrumed at 85. To an arm 99 forming a part of the segment 98 is attached a link 100 which is connected to a slide 101 mounted upon a tie rod 16 and similar to the slide 88 previously described. The slide 101
 40 is also provided with a stud and cam roller 102 which travels in a cam groove 103 in the stationary cylinder 104.

50 The grooves 90 and 103 are so related to each other that the vertical position of the spinning rolls and the pressure of the rolls upon the sleeves are coöordinated with each other so that the sleeves are subjected to a spinning process and simultaneously to a drawing or ironing out process as well.

55 It will be noticed also that the mechanism controlling the position of the spinning rolls and the mechanism controlling the pressure of the rolls are independent of each other and that each is controlled by the particular 60 form of cam groove which causes its movement. The machine is therefore adapted to bring any desired pressure to bear upon the spinning rolls at any particular position into which the rolls may be moved. Each 65 function of the spinning mechanism is there-

fore capable of being independently as well as coördinately controlled.

In the present instance, this is taken advantage of to increase the pressure of the rolls directly with their downward movement, the cam grooves being plotted for this purpose, so that the joining sleeve is held under an increasing drawing tension during the spinning operation, resulting in an unusually tight and permanent joint.

Furthermore the resilient members 92, 92 are adapted to yield slightly should the spinning rolls strike an obstruction or imperfection either in the ferrule or the bottle neck and the rolls will ride over such an obstruction avoiding breakage and at the same time completing a satisfactory sealing operation.

The invention is disclosed in connection with a mechanism specially adapted for the sealing of caps to non-refillable bottles; but it is to be understood that the invention is not restricted to this particular illustrative mechanism as it also includes all machines in which necks and receptacles of any description are sealed together. It is obvious also that many changes may be made in the details of the mechanism disclosed without departing from the spirit of the invention. The spinning rolls described and shown may be replaced by non-rotary spinning tools in the nature of a simple burnisher; for the can grooves controlling the different movements of the spinning mechanism other mechanical devices may be employed to effect the purposes of the invention; in addition to these many other changes are possible, so that the invention is not to be limited to the particular structure and the specific details herein disclosed.

What is claimed:

1. In an apparatus for uniting a bottle neck to a bottle by a connecting sleeve, the combination, with means for centering the neck upon the bottle, and means for clamping the sleeve in position, of a spinning tool, means for revolving said tool about an axis substantially parallel to the axis of the neck, means for moving the tool longitudinally in relation to said axis, and means for pressing the tool against the sleeve with a progressively increasing pressure. 110 115

2. In an apparatus for uniting a bottle neck to a bottle by a connecting sleeve, the combination, with a centering device arranged to enter the mouth of said bottle neck and press the neck toward the bottle, of a tubular clamping device arranged to clamp one end of the sleeve against the bottle neck, and means for spinning the sleeve into engagement with the bottle neck and bottle. 120 125

3. In an apparatus for uniting a bottle neck to a bottle by a connecting sleeve, the combination, with a centering device ar- 130

ranged to engage the end of the bottle neck to center the same and press it against the bottle, and a clamping device arranged to clamp the sleeve against the bottle neck, of a spinning tool, means for revolving said tool about an axis substantially parallel to the axis of the neck, means for moving the tool substantially in relation to the axis, and means for pressing the tool against the sleeve with a progressively increasing pressure.

4. In an apparatus for uniting a bottle neck to a bottle by a connecting sleeve, the combination, with a centering device arranged to enter the mouth of said bottle neck and press the neck toward the bottle, of a tubular clamping device arranged to clamp one end of the sleeve against the bottle neck, and resilient means for spinning the sleeve into engagement with the bottle neck and bottle.

5. In an apparatus for uniting a bottle neck to a bottle by a connecting sleeve, the combination, with a centering device arranged to engage the end of the bottle neck to center the same and press it against the bottle, and a clamping device arranged to clamp the sleeve against the bottle neck, of a resilient spinning tool, means for revolving said tool about an axis substantially parallel to the axis of the neck, means for moving the tool longitudinally in relation to the axis, and means for pressing the tool against the sleeve with a progressively increasing pressure.

In testimony whereof, I have hereunto set my hand, in the presence of two subscribing witnesses.

JOSEPH D. LACROIX.
